WATER HEATER

John E. Synnott, Hartford, Conn., assignor to
John Joseph Synnott, West Hartford, Conn.

Application January 29, 1935, Serial No. 3,935

5 Claims. (Cl. 122—333)

This invention relates to apparatus for heating water and particularly to the type of water heaters which comprises a plurality of tubes connected between a pair of end members which provide headers for the structure of the heater body; the water being supplied thru a supply pipe into one of the end members and then distributed, thru the tubes, into the opposite end member and from there out thru an outlet pipe. The total capacity of the tubes, being much greater than that of the supply pipe, the water flow is greatly retarded therein so that it will have an ample opportunity to be heated while passing thru the tubes.

15 In devices of this kind, it has heretofore been the practice to construct the heater body by means of cast iron ends to which the tubes are brazed. It has been found that the cast iron ends cannot be depended upon; for the reason 20 that they are very apt to be porous and, in most cases, the porous condition cannot be detected until the heater has been in operation for a considerable length of time and, when a leak occurs in the heads, it is very difficult to repair 25 them, thus making the use of cast iron heads very undesirable.

The object of this invention, among others, is primarily to provide for a water heater, a body 30 which is of the lightest possible construction and in which the use of cast iron water conduits are entirely eliminated.

Another object of this invention is to provide 35 such a body, for a water heater, which is economical to produce and efficient to a maximum degree in its operation.

My invention is illustrated in the accompanying drawing in which:

Figure 1 is a view in central vertical section thru 40 a water heater; the body of the heater being shown partly in elevation.

Figure 2 is a plan view of the body of the heater, in section, on line 2—2 of Figure 3.

Figure 3 is a view in central vertical section of the same.

45 Figure 4 is a fragmentary view illustrating the manner in which the connecting tubes are secured to the headers.

Figure 5 is a fragmentary view illustrating a modified form of construction for the headers.

As shown in the drawing in which like numerals denote like parts, my improved heater comprises mainly a heater body 5 which consists of similar end members or headers 6—6. Each of these headers is constructed of annular tubular rings consisting of an inner ring 7 and an outer

ring 8, which are formed of tubes bent into rings and brazed at the abutting ends as at 7—a and 8—a. A water pipe 9 is connected to each of the said headers. The said water pipe is centrally located and attached to the inner ring by the radially extending tubular sections 10, and the outer ring is connected to the said inner ring by the tubular sections 11 extending therebetween.

A number of holes 12 are formed into each of said rings. The ends of the water tubes 13 are inserted into said holes and attached to said rings by suitable means, such as brazing. The said water tubes when attached to the rings form concentric rows 14 and 15.

The method of attaching the tubular rings to the water tubes is clearly shown in Figure 4 of the drawing. As shown therein, each of the holes 12 is provided with a shoulder 16 against which abut the ends of the water tubes 13. The connecting tube 11 shown in this figure, extends thru a hole 17 and both the said connecting tube and the water tubes are securely united with the ring member by suitable means, such as by brazing, as indicated at 18.

In the construction illustrated in Figure 5 of the drawing, instead of connecting the rings by means of the tubular sections 10 and 11, the said rings are connected by the tubular sections 19 which extend from the water pipe 9 past the inner ring 7, to the outer ring 8. Said section 19 has a hole 20 registering with a notch 21 in the ring 7 and the end of said section extends into an opening 22 in the outer ring. The said rings and connecting sections are united by the brazing 25 30 35 40 45 50 55 60 65 70 75 80 85 90 95 100 105 110 115 120 125 130 135 140 145 150 155 160 165 170 175 180 185 190 195 200 205 The heater body may be secured to the gas burner by means of a set screw 32 which is threaded to the hub 33 of the plate 24.

A combustion retarding plate 34 is mounted at the top of the heater body to retard the heat of combustion around the water tubes 13. A cap 35 is mounted over the said plate and extends into a flue 36.

It can be readily seen that in the heater illustrated in Figure 1, the tubular structure, which comprises the heater body rests upon the gas plate 27, and that the gas jets 28 extend upwardly between the annular rings forming the lower header, and also within the inner ring. Said jets extend to a position substantially above the said header.

In the operation of the above described heater, the water is supplied thru the water supply pipe 10 into the lower header 6, from there it will flow upwardly, thru all of the tubes 13, into the upper header 6 and from there into the water outlet pipe 9. It will be understood the total capacity of the tubes 13 is much greater than that of the supply pipe 10 or outlet pipe 9. This will cause the flow of water to be greatly retarded as it passes thru the tubes 13, thus permitting the water to absorb the maximum amount of heat from the combustion of the gases as the water passes thru said tubes. When the water reaches the outlet pipe 9, thru the upper header 6, the capacity being the same, the flow will be again the same as thru the supply pipe 10.

By my invention I have provided a heater body which may be constructed entirely of tubes. All of the tubes comprising said body may be of the same material, thus rendering it possible to form a much more satisfactory brazing connection between the various members than can now be formed where the brazing is done between a tube, of such material as brass or copper, and a header of cast iron. At the same time I have also provided a structure which is of minimum weight and of maximum efficiency.

I claim:

1. A liquid heater of the character described comprising a body composed of end members which are constructed of a plurality of annular tubular members concentrically disposed, a pipe communicating with each of said end members, and a plurality of tubular members interconnecting said end members, a burner positioned ad-

jacent an end member of said body, and a jet for delivering the products of combustion thru the said end member.

2. A liquid heater of the character described comprising a body composed of end members which consist of a plurality of tubular annular members concentrically disposed and having annular openings therebetween, radial tubular members interconnecting said annular members, a pipe communicating with said radial members, a plurality of tubes interconnecting said end members, a burner adjacent to an end member of said body and jets on said burner adapted to deliver the products of combustion thru said annular openings into said body. 15

3. A liquid heater of the character described comprising a housing, a heater body constructed entirely of tubes and consisting of annular end members, a plurality of tubes inter-connecting the same, and a pipe communicating with each of said end members, a burner comprising a dish shaped plate adapted to form a gas chamber and having a hub whereby the said plate may be secured to one of said pipes, a burner plate overlying said gas chamber, jets extending upwardly from said burner plate and projecting thru one of said end members into said body for delivering products of combustion therein. 20

4. A liquid heater of the character described comprising a body composed of end members which are constructed of a plurality of spaced annular tubular members concentrically disposed, a pipe communicating with each of said end members, a plurality of tubular members inter-connecting said end members, a burner positioned adjacent an end member of said body and jets on said burner disposed in alignment with the spaces between said annular tubular members for delivering the products of combustion thru the said end member. 35 40

5. A heater of the character described comprising a body having end members constructed of a plurality of annular tubular members interconnected by radial tubes, a pipe communicating with said radial tubes on each of said members, a plurality of tubes interconnecting said end members, a burner secured to said pipe, and jets on said burner constructed to deliver the products of combustion thru the said end member. 45 50

JOHN E. SYNNOTT.
